Sigmund Herzog
ATTORNEY

UNITED STATES PATENT OFFICE.

MILTON LOWY, OF PORT CHESTER, NEW YORK.

TRAVELING BAG.

Application filed January 16, 1925. Serial No. 2,806.

To all whom it may concern:

Be it known that I, MILTON LOWY, a citizen of the United States, and resident of Port Chester, in the county of Westchester and State of New York, have invented certain new and useful Improvements in Traveling Bags, of which the following is a specification.

The present invention relates to improvements in traveling bags of the type commonly known as suitcases, and has for its main object to provide a receptacle of this type in which strength and durability are combined with comparatively low cost of production.

Another object of the invention is to provide a simple and efficient means for the support of the lid on the body of the bag, whereby the parts are tightly joined and guided in opening and closing.

With these and other objects in view, which will more fully appear as the nature of the invention is better understood, the same consists in the combination, arrangement and construction of parts hereinafter described, pointed out in the appended claims and illustrated in the accompanying drawings, it being understood that many changes may be made in the size and proportion of the several parts and details of construction within the scope of the appended claims, without departing from the spirit or sacrificing any of the advantages of the invention.

35 One of the many possible embodiments of the invention is illustrated in the accompanying drawings, in which:—

Figure 1 is a vertical transverse section taken through a bag constructed in accordance with the present invention, the same being shown in open position; and Fig. 2 is an enlarged fragmentary transverse section of the edges of the body and lid of the traveling bag in positions they occupy when the bag is closed.

In the drawings the numeral 10 indicates the body portion of the suitcase, and the numeral 11 the lid of the same. These two elements are joined by hinges 12, and they are, as usual, provided with a lock and handle, not shown. Catches 13 are provided for the well known purpose.

The body of the suit case may be made of vulcanized fibre 14, leather or other ma-

material of similar nature, shaped to provide a rectangular open receptacle. The sides of the receptacle are reinforced by a wooden frame 15, which is disposed within the same but extends a substantial distance above the open top thereof, as shown at 16. The upper edges 17 of the receptacle form thus a shoulder below the upper edges of the frame 15, for a purpose hereinafter to be described. If the receptacle is made of fibre or similar material, the same may be provided with an outer covering 18 of artificial leather or the like, the said cover extending over the shoulder 17 and thence around the portion 16 of the frame 15, terminating on the inner face of the said frame a little distance below the upper edges thereof. Upon the inner surface of the wooden frame and the inner face of the bottom portion of the element 14 is provided a lining 19, the said lining being glued to the frame and fibre element 14, or otherwise secured thereto.

The lid 11 is likewise made of fibre 20 or other similar material, corresponding with the body of the case to which it is attached. The sides of the lid are reinforced by a wooden frame 21, which is wholly disposed within the lid, it being of a depth substantially less than that of the lid. The arrangement is such that, when the lid is brought to closing position, the free edges of the wooden frame 21 rest upon the upper edges of the wooden frame 15 of the body 10. The fibre or similar material 20 of the lid is provided with a covering 22, which may be extended over the inner face of the wooden frame 21, thereby also forming a lining for the latter. The top portion of the lid may also be provided with a lining, denoted by the numeral 23.

Both the body portion of the case and 95 the lid are, as usual, reinforced by corner pieces 24, made of leather or other wear resistant substances.

When the lid is in its closed position, its free edges overlap the upper edges of the wooden frame 15 of the body 10 by reason of the fact that the said last-mentioned upper edges are offset in relation to the upper edges of the fibre receptacle 14. In these positions the free edges of the wooden frame 21 of the lid are supported by the upper edges of the wooden frame 15 of the case; the parts thus support each other

against collapse and are tightly joined to protect the contents of the case against dust and moisture.

What I claim is:—

- 5 1. A suit case comprising a box-shaped body part, a box-shaped lid adapted to close the same, a reinforcing frame within and resting against the bottom wall of said body part and having its upper edges projecting above said body part, and a reinforcing frame within and resting against the top of said lid and having its free edges disposed so that the free edges of said lid project beyond the same, whereby the projecting portions of said lid are brought against the outer faces of the projecting portions of the frame of said body part and the frame of said lid engages the upper edges of the frame of said body part when the lid is in its closed position, the reinforcing frames together being coextensive in length and width with the side and end walls of the suit case, the engaging surfaces of the lid and the upper edges of the frame of the body part being of a shape that there is no tendency for one to slide over the other on account of pressure applied to the top and bottom of the suit case.
- 10 2. A suit case comprising a box shaped body part, a box shaped lid adapted to close the same, and rectangular reinforcing frames within and coextensive in length and width with the side and end walls of the body and the lid parts and adapted to have end to end contact with each other when the lid is
- 15
- 20
- 25
- 30
- 35

closed thereby reinforcing the suit case throughout all of the side walls thereof, the upper edge of the body part on all sides being reduced in thickness on the outer face thereof and the walls of the lid extending below the top edge of the reinforce within the body portion to flushly fit within the reduced portion of the body part, the engaging surfaces of the lid and the upper edges of the frame of the body part being of a shape that there is no tendency for one to slide over the other on account of pressure applied to the top and bottom of the suit case.

3. A suit case comprising a box shaped body part, a box shaped lid adapted to close the same, and reinforcements within and resting against the bottom and top walls of the body and lid parts respectively, said reinforcements being coextensive in length and width with the side and end walls of the body and the lid parts and adapted to have end to end contact with each other when the lid is closed thereby reinforcing the suit case on all of the side and end walls thereof the engaging surfaces of the lid and the upper edges of the body part being of a shape that there is no tendency for one to slide over the other on account of pressure applied to the top and bottom of the suit case.

Signed at New York, in the county of New York, and State of New York, this 13th day of December, A. D. 1924.

MILTON LOWY.
